(57) **CLAIM**

The ornamental design for a dual telematics camera, as shown and described.

DESCRIPTION

FIG. 1 is a top, front and left side perspective view of a dual telematics camera;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The shade lines in the drawings depict the contour of the surfaces and not surface ornamentation.

The broken lines depict portions of the dual telematics camera in which the design is embodied that form no part of the claimed design.
